UNITED STATES PATENT OFFICE.

JOSEPH S. O'BRIEN, OF SPRINGFIELD, MASSACHUSETTS.

RATCHET-AND-PAWL DEVICE.

SPECIFICATION forming part of Letters Patent No. 252,962, dated January 31, 1882.

Application filed December 8, 1881. (No model.)

To all whom it may concern:

Be it known that I, JOSEPH S. O'BRIEN, a citizen of the United States, residing at Springfield, in the county of Hampden and State of 5 Massachusetts, have invented new and useful Improvements in Ratchet-and-Pawl Devices, of which the following is a specification:

The invention relates to improved ratchet-and-pawl devices for mowing-machines and 10 other uses, the object being to provide such devices which are strong and positive in their operation, but above all perfectly noiseless, so that when the motion of said machines is reversed the usual ratchet noise made by them 15 will be obviated.

In the drawings forming part of this specification, Figure 1 illustrates one end of a mowing-machine drum having applied thereto ratchet-and-pawl devices constructed according 20 to my invention. Fig. 2 is a view of the pawl disk or plate. Fig. 3 is a view of one of the pawls, and Fig. 4 is a segment of the ratchet-ring.

In the drawings, A is the drum. B is the 25 ratchet-ring. c c are the pawls. d is a shaft. o o are pins placed in a collar, i, on said shaft, or directly therein, and standing at right angles to its axial line; and h is a grooved pawl-disk.

The shaft d is fixed in the drum A and 30 adapted to turn with it, and has fixed therein, in a collar, i, thereon, two pawl-pins, o o, standing at right angles to said shaft and upon opposite sides thereof.

The pawl-disk h is bored to slip over collar 35 i on shaft d, and has two grooves, x x, formed in one side thereof to receive the pawl-bars c e, the latter being notched to receive pins o o.

The ratchet-ring B in this application of the 40 ratchet-and-pawl devices has a gear formed on its periphery, to provide means for direct connection between drum A and the cutter-bar shaft of a lawn-mowing machine, and said

ratchet-ring is by any well-known construction of such wheels made with arms or a solid 45 back provided with a central hub to fit on shaft d back of collar i, so that said ring and gear will turn freely on said shaft.

The parts of the ratchet devices are mounted on shaft d and within the ring B in the positions shown in Fig. 1, and operate as follows: When drum A turns in the direction indicated by the arrow thereon pins o o on shaft d will be driven in opposite directions, and each will carry one of the pawls c toward the periphery 55 of disk h, causing the outer beveled ends of said pawls to engage with the teeth of the ratchet-ring B and revolve the latter by the rotation of said drum; but when the motion of the latter is reversed the said pawls are 60 drawn back away from ring B and clear from it, and disk h and said pawls revolve noiselessly within said ring.

It will be seen by the above description of said ratchet-and-pawl devices that the movement of the pawls both toward and from the ratchet-ring is positive, no springs being relied upon, and that they will surely act regardless of the position of the parts.

The within-described application of said 70 ratchet-and-pawl devices is only one out of many to which it may with advantage be adapted.

What I claim as my invention is—

The within-described improved ratchet-and-pawl device, consisting of the shaft d, having the pins o o therein, the pawls c c, notched to receive said pins, the disk h, grooved to receive said pawls in the face thereof, and the ratchet-ring B, all combined and operating 75 substantially as set forth.

JOSEPH S. O'BRIEN.
